UNITED STATES PATENT OFFICE.

LUTHER A. GAW, OF CHARLOTTESVILLE, VIRGINIA.

INTERNAL-COMBUSTION ENGINE.

1,286,275.

Specification of Letters Patent.

Patented Dec. 3, 1918.

Application filed July 24, 1916. Serial No. 110,996.

To all whom it may concern:

I, LUTHER A. GAW, a citizen of the United States, and resident of Charlottesville, in the county of Albemarle and State of Virginia, have invented a certain new and useful Improvement in Internal-Combustion Engines, of which the following is a specification.

My present invention relates to internal combustion engines and more particularly to such embodying a reciprocable shell valve within the cylinder for controlling the intake and exhaust, the piston working within said shell valve.

The principal objects of my invention are to provide an internal combustion engine of the character described, which embodies lubricating means operated from the same shafts as are used for the control of said shell valve; valve mechanism for internal combustion engines which will cease to operate if there is not sufficient lubricating oil introduced about the shell valve, or should the engine become overheated, the valve remaining inert with the intake port open under such abnormal conditions giving due warning to the operators; valve mechanism for internal combustion engines embodying non-rotatable shell valves, which are inert except when either their respective intake or exhaust ports are open, thus reducing wear upon the valves to a minimum; valve mechanism for internal combustion engines embodying reciprocable shell valves, the said valves traveling in the same direction as their respective pistons for a portion of the stroke; and an internal combustion engine of the character described embodying means for lubricating the valves above and below their respective intake and exhaust ports, the oil being forced about the valves, and delivered to suitable oil sumps into which the piston rods dip, lubricating the valve control means.

Other objects of my invention will appear in the following detailed description taken in connection with the accompanying drawings, forming a part of this application, and in which drawings:

Figure 1 is a central vertical sectional view through an engine embodying my invention, parts being shown in elevation in order to more clearly disclose details.

Fig. 2 is a central vertical sectional view

through said engine at a right angle to that shown in Fig. 1.

In the drawings, where similar characters refer to similar parts throughout the views, A designates a cylinder; B a cylinder head; C a crank case; D a shell valve reciprocable in cylinder A; E a trunk piston reciprocable in valve D; F and F' a crank and crank shaft, respectively; G a rod operatively connecting piston E with crank F; H valve control means; I lubricating mechanism; J means for controlling mechanism I; and, K motion transmitting means operatively connected with shaft F' for operating means H and J.

Referring first to the cylinder A, while I have herein shown the invention applied to a single cylinder internal combustion engine, it is to be understood that the invention is applicable to engines embodying a plurality of cylinders and under which conditions, the structures are much simplified over what is now common in the art. The cylinder A may be provided with a jacket 3 which extends about the combustion chamber of the engine and has communication with a jacket 4 of cylinder head B, the ingress to the jacketing being as at 5 and the egress as at 6. An intake port for the charge is designated as at 7, and an exhaust port 8 for the waste products of combustion, these ports being preferably diametrically opposite one another.

It is preferred to construct the head B with a drum-like extension 9, of a diameter relatively less than the internal diameter of cylinder A, said drum-like extension to project within cylinder A when the head B is secured in operative relation to the cylinder, providing an annular groove 10, bounded by the cylinder A, extension 9, and the internal face of head B. An annular groove 11 is provided at the external periphery of extension 9, for a purpose to be subsequently set forth, and the head, through bore 12 may accommodate a spark plug 13 or other ignition device having its terminals within the combustion chamber.

As to the crank case C, it may comprise a flange 14 integral with, or carried by cylinder A; a base 15 formed to provide an oil sump 16; and, an intermediate portion 17 joining base 15 with flange 14. The various sections of the crank case may be

secured together as by bolts 18, so that they are readily detachable to facilitate repair. Referring now to the cylindrical shell valve D, which fits nicely within the cylinder A, it is adapted to extend into groove 10, at head B, as indicated at 19, while the portion 20 opposite thereto preferably extends into the crank case C. The valve D is provided with an intake port 21 adapted to register with 10 intake port 7 of cylinder A; and an exhaust port 22 adapted to register with exhaust port 8 of said cylinder, the ports 21 and 22 being at opposite wall portions of the valve, but not diametrically opposite one another, 15 in the example shown. The port 21 is centered in a transverse plane spaced substantially three times the width of port 7 or 8 from a similar plane in which port 22 is centered, so that as the valve D is reciprocated, it successively opens the exhaust and 20 intake ports. A packing ring 23 may be disposed in annular groove 11, bearing against the internal periphery of valve D at its portion about extension 9 of head B, said 25 ring preventing lubricating oil from passing into the combustion chamber, to any material extent, and aiding in maintaining compression within the cylinder A.

The piston E may be of any suitable construction, of a diameter to fit nicely within shell valve D, and in the example shown, is provided with piston rings 24 engaging internal periphery of valve D. Likewise the crank F and shaft F' may be of any 30 suitable construction, and in the example shown, the crank F is operatively connected with piston E as through connecting rod G, oscillatable about pivot 25, at piston E and provided with a bearing 26 at crank F, said bearing including a finger 27 adapted to dip in oil sump 16 to splash the oil for lubricating purposes as hereinafter set forth.

In order that movement of valve D may be controlled for successful operation thereof during the intake, compression, power and the exhaust strokes of the engine, means H is provided, which, in the example shown, comprises positive mechanism 28, such as a cam 29 acting upon a roller 30, said roller supported by an arm 31 extending from the lower portion of valve D; and, non-positive or force-closed mechanism 32 such as a spring 33 and encircling a stem 34, said spring 33 compressed between the flange 14 of crank case C and said arm 31. The cam 29 is rotatable about an axis 34, said cam having a working periphery 35, equidistant from its center 34 for substantially 180°; a concave working periphery 36 for substantially 90°; and, a convex working periphery 37 for the remainder,—90°, the circumference of roller 30 bearing upon these working faces in succeeding relation. The cam is so arranged that, when said roller bears upon the working face 35 which is

substantially equidistant from its center 34, neither of the ports 21 nor 22 are open to their respective ports 7 and 8, so that during compression and power strokes, there is no escape for the gaseous fluid from cylinder A. When the roller 30 engages the working face 37 or in other words, the throw of the cam, the valve D is moved so that port 21 opens port 7 to the interior of cylinder A, and when the roller 30 drops into the depression or engages the working face 36, the valve D is moved so that port 22 opens port 8 to the interior of cylinder A for the exhaust of waste products of combustion. As to mechanism 32, while I have herein 80 shown the same embodying the elements 33 and 34, it is to be understood that any practical type of non-positive or force-closed mechanism may be used. In the example shown, the stem 34 extends through a bore 85 38 in crank case being disposed with its axis parallel to the longitudinal axis of valve D, a suitable cap 39 being provided to cover that portion of stem 34 which is exteriorly of case C. The stem 34 has the dual function of preventing circumferential movement of the valve D and also serves as a retainer for spring 33, maintaining the same in operative relation to the valve D.

Lubrication mechanism I, in the example 95 shown, comprises a pump 40 including the cylinder 41 and piston 42, the latter of which may be provided with an enlarged head 43; a check valve 44 adapted to control the passage of oil from a suitable chamber 100 45 below oil sump 16, a port 46 affording communication between said oil sump and chamber 45; a suitable check valve 47 preventing back flow of oil directly after it has been forced from the cylinder 41; and 105 suitable conducting means 48 which delivers the oil forced from pump 40 to the portion 19 of valve D about extension 9 of head B, the egress of conducting means 48 being indicated at 49, passing through the jacketing 110 3 and cylinder A. Thus, as the piston 42 of pump 40 is reciprocated, the oil is drawn from chamber 45 into cylinder 40 as through port 50 and is forced past check valve 47 115 through conducting means 49 to that portion of valve D opposite to oil sump 16, the oil being under pressure. Thus the valve D is effectively lubricated, the oil circulating about the valve D above and below its ports 21 and 22, and finally is delivered to oil 120 sump 16 where it is again utilized either for lubrication of the means H and J, as well as the pump 40, as when the finger 27 dips into the oil sump and throws the oil toward portions of the engine, or is again used in 125 lubricating the valve D. If desired, a strainer 51 may be provided intermediate the port 46 and port 50, said strainer being in chamber 45, and suitable drains 52 and 53 may be provided at the lower portion of 130

chamber 45 and the lower portion of the bore of cylinder 41 respectively. As to means J for controlling the lubricating mechanism, it may comprise positive mechanism 54, such as a cam 55, rotatable about axis 34, said cam bearing upon the enlarged head 43 of piston 42, exteriorly of cylinder 41, the throw of the cam being designated 56; and, a spring or non-positive mechanism 57 within the bore of pump 40 and engaging the working face of piston 42, said spring being interposed between said piston and the end of cylinder 41 opposite to head 43.

15 Referring now to the motion transmitting means K, for operation of the means H and J, it is desirable to operate said last mentioned means at a uniform speed ratio from crank shaft F and the motion transmitting means K may comprise a gear 58 rigid with shaft F'; a second gear 59 co-meshing with gear 58, and a shaft 60 rigid with gear 57 and extending transversely through crank case C, the cams 29 and 55 being rigid with shaft 60 internally of crank case C. The circumference of gear 59 is substantially twice that of the circumference of gear 58 so that for each two complete revolutions of crank shaft F', the shaft 60 is revolved once, or in other words, passes through one phase of movement. A combination oil filler pipe 61 and breather 62 may be provided in communication with crank case C, as clearly shown in Fig. 1 of the drawings.

30 35 The operation of the engine is as follows: As shown in the drawings, the piston E is slightly past the start of the intake stroke, the shaft F' rotating in the direction indicated by an arrow, and the shaft 60, rotating as indicated by arrow. It is to be observed that the roller 30 is in engagement with the start of working face 37 of cam 29, which engagement raises the valve D so that the port 21 of valve D is open to intake port 7. As the piston E descends for intake of the charge, during one-half of its phase of movement, the valve D moves in an opposite direction, however, the second half of the phase of movement, the valve D, responsive to non-positive mechanism 32 moves in the same direction as the piston E. As the piston E ascends, for the compression stroke, the roller 30 rides upon the working periphery 35 of cam 29, and neither ports 21 nor 22 are open to their respective ports 7 and 8, respectively. This condition exists during the power stroke or descending of the piston, the valve D being inert during the effective compression and power strokes. 40 45 As the piston E again descends for exhaust of the waste products of combustion, the roller 30 drops into the recess or engages the working periphery 36 of cam 29, responsive to action of spring 32, and the exhaust port 22 is alined quickly with exhaust port 8, it

being preferred to so construct cam 29 that the drop at working periphery 36 will be abrupt and will quickly open the exhaust port, reducing back pressure within the combustion chamber of the engine, to a minimum.

45 It is to be observed that, if the valve D should fail to reciprocate readily, due to lack of lubrication, or owing to overheating of the engine, said valve would stick or adhere to the internal periphery of cylinder A with the port 21 open to port 7, inasmuch as the said valve is actuated to such position by positive mechanism, but under normal conditions, is moved from such position by non-positive or force-closed mechanism. Thus under abnormal conditions, the operator would be notified of insufficient lubrication or over heating, there being little or no compression in the engine with the intake port 80 open during the compression stroke.

50 As the finger 27 dips into oil sump 16, the oil is thrown through port 46, about head 43, cams 29 and 55, roller 30 and against the internal periphery of valve D.

55 Changes in details may be made without departing from the spirit or scope of my invention; but,

I claim:—

1. In an internal combustion engine, the combination of a cylinder provided with intake and exhaust ports, a cylindrical shell valve within said cylinder provided with ports adapted to open to said ports of said cylinder and being arranged in vertically offset relation in planes adapted to lie at times one above and one below the respective ports of the cylinder, a piston in said valve, and means for shifting said valve to aline co-operating ports for intake during the intake stroke of said piston, said piston being adapted to shift the valve by frictional contact therewith to aline co-operating ports for exhaust during the exhaust stroke of said piston, said valve being inert except when moving to open and close said intake or exhaust ports.

2. In an internal combustion engine, the combination of a cylinder provided with intake and exhaust ports, a shell valve within said cylinder provided with ports adapted to be open to said ports of said cylinder, a piston in said valve, and means including positive mechanism for moving said valve to open co-operating ports for intake of the charge, said piston by frictional contact therewith being adapted to move said valve to close said ports.

3. In an internal combustion engine, the combination of a cylinder having lateral intake and exhaust ports, a sleeve valve in the cylinder having corresponding ports therein, a piston movable in the sleeve, and means for positively shifting the sleeve valve to register a port thereof with the intake port

of the cylinder, said sleeve valve being adapted to be shifted into an opposite position by frictional contact with the piston to register another port of the valve with 5 said exhaust port of the cylinder, said sleeve valve also being adapted to stick in its positively shifted position upon the overheating of the engine to maintain the exhaust port closed.

- 10 4. In an internal combustion engine, the combination of a cylinder provided with intake and exhaust ports, a cylindrical shell valve within said cylinder provided with ports adapted to be open to said ports of 15 said cylinder, a piston in said valve, a crank case and crank shaft, a rod operatively connecting said piston with said crank shaft, a stem reciprocable with said valve extending parallel to the longitudinal axis thereof and guided against lateral movement by said crank case, an expansion spring about said rod acting upon said valve to move the same to close coöperating ports after intake and open coöperating exhaust ports, a cam acting upon said valve to move the same to open coöperating ports for intake of the charge and to close exhaust ports, and motion transmitting means between said crank shaft and cam.
5. In an internal combustion engine, the combination of a cylinder provided with intake and exhaust ports, a shell valve within said cylinder provided with ports adapted to open to said ports of said cylinder, and an 35 arm extending laterally at its lower portion, a crank case and crank shaft, a rod operatively connecting said piston with said crank shaft, a stem rigid with said arm, extending parallel to the longitudinal axis of 40 said cylinder and guided against lateral movement by said crank case, an expansion

spring about said rod and interposed between said crank case wall and said arm, to move said valve in one direction, a cam acting upon said arm to move the valve in the other direction, and motion transmitting means between said crank shaft and said cam.

6. In an internal combustion engine, the combination with a cylinder provided with intake and exhaust ports, a piston, crank shaft, and rod operatively connecting said piston and shaft of a shell valve interposed between said piston and cylinder for controlling said ports, lubricating mechanism for said shell valve, means for controlling said lubricating mechanism, means for shifting said shell valve to open the intake port, and motion transmitting means operatively connected with said crank shaft for operating said control means for said lubricating mechanism and said shifting means for the shell valve, the valve being adapted to move into position to open the exhaust by frictional contact with the piston and to bind in the cylinder with the intake port open upon the failure of the lubricant.

7. In an internal combustion engine, the combination of a cylinder provided with an intake port, a shell valve within said cylinder provided with a port adapted to open to said intake port of said cylinder, a piston in said valve, and means including positive mechanism for moving said valve to open said port for intake of charge, and non-positive mechanism including the piston for moving said valve to close said port and admit sticking of the valve with the intake ports in register upon exhaust of lubricant on the valve.

LUTHER A. GAW.
